UNITED STATES PATENT OFFICE

NIELS LANG, OF CLEVELAND, OHIO

REFLECTOR FOR DIRECTING LIGHT

Application filed January 26, 1926. Serial No. 83,813.

My invention relates to reflectors composed of a plurality of reflecting surfaces oppositely inclined toward each other, designed to distribute light more ideally over 5 the space desired, with a smaller reflector than that which would be required for like distribution of light if made otherwise. An object of the invention is to provide light reflectors that are substantially smaller in 10 size for any specific purpose, so that they may be more easily concealed and more economically manufactured, while a further object of the invention is to permit the reflecting surfaces to be at a minimum distance 15 from the source of light, to trap every available light ray and prevent waste. The invention is particularly applicable to industrial lighting and to display lighting. This application is a continuation in part of my 20 prior application patented April 26, 1927, Patent No. 1,625,948, and my prior application patented October 22, 1929, Patent No. 1,732,582.

Heretofore in constructing reflectors for 25 such purposes, a continuously curved, compounded or spiraled, peripheral surface extended laterally from the neck of the reflector and reached a comparatively large maximum perimeter before the light emitted was 30 sufficiently confined, or projected as desired.

Such reflectors are somewhat difficult to 35 conceal in show-windows, etc., requiring too much space where intense concentration of light is necessary and due to their bulk are comparatively expensive to manufacture. Reflectors constructed according to my invention are more desirable for such purposes.

In constructing a reflector according to 40 the present invention for reflecting light rays from an incandescent lamp, an outwardly reflecting surface (starting at the neck of the reflector) is extended laterally outward and preferably terminates before its perimeter is two and one-quarter times that 45 of the maximum perimeter of the lamp. From this an oppositely inclined surface is laterally disposed inwardly to a sufficient extent to allow a second outwardly inclined surface to be projected laterally therefrom, preferably without this maximum perimeter

exceeding the maximum perimeter of the lamp, two and one-quarter times. In this manner as many oppositely inclined surfaces can be constructed, as may be necessary to sufficiently confine the light, or to distribute 55 or concentrate it over the desired area of illumination.

Further and more specific objects, features and advantages will more clearly appear from the detail description given below taken 60 in connection with the accompanying drawings which form a part of this specification and which illustrate the application of the invention to certain forms of reflectors and from which those skilled in the art will readily understand the applicability of the invention 65 in the making of other kinds and forms of reflectors.

Fig. 1 is a vertical section of a reflector in the plane of its axis;

Fig. 2 is a similar view of a reflector designed to effect a wider distribution of light;

Fig. 3 is a vertical section of a light reflector taken through one axis, which effects 75 a particular form of light distribution;

Fig. 4 is a plan view of the reflector shown in Fig. 3; and

Fig. 5 is a vertical section of an asymmetrical reflector.

Referring to the accompanying drawings by corresponding reference characters throughout, the numeral 6 indicates the neck of the reflector by which the reflector is connected to its support, and from this neck 6 a reflecting surface 7 is extended laterally outward and contoured so that the light rays emitted by the filament or light source 8 which it intercepts, are reflected in the directions desired without passing back through the said filament 8. The said surface 7 is preferably terminated when it is sufficiently large to permit the interior periphery of the inverted and oppositely inclined surface 9 to clear the lamp bulb 10. The inverted surface 9 is inclined so that all light rays it may intercept are reflected inwardly, preferably to the surface 7 for subsequent reflection. Another reflecting surface 11 is projected laterally forward of such contour that 100

all rays it reflects are projected outward from the reflector in the desired directions. Another inverted surface 12 is connected thereto, inclined at an angle substantially parallel to a light ray reflected from the surface 11; the interior size of the said surface 12 is large enough to permit the passage of the lamp bulb 10 in and out of the reflector. An outward reflecting surface 13, connected to the inverted surface 12, extends laterally forward so that the light emitted is confined to the space desired. The surface 13 is properly contoured to direct the light rays outwardly over the desired area.

A modification of the same method of constructing a reflector is shown in Fig. 2. This reflector is designed to effect a less concentrated distribution of light than that of Fig. 1, the focal point indicated by the light source 8 being located farther forward. The neck 6 is tapered to clear the lamp bulb 10; the outward reflecting surface 7 and oppositely inclined surface 9 are constructed substantially like those in Fig. 1, but the outward reflecting surface 7 is continued laterally forward until it cuts off the light at the desired angle without necessitating another step. To effect the proper distribution of light, the contour necessitated results in the maximum perimeter of the surface 11 being greater than that of the surfaces 7 or 9.

Another application of this method of constructing reflectors is shown in Figs. 3 and 4, in which a reflector is shown which distributes the light differently on two opposite sides of the light source, and cuts off the light emitted at different angles. In these figures an outwardly reflecting surface 14 is extended laterally forward from the neck 6, joined by an oppositely inclined surface 15 to a second outwardly inclined reflecting surface 16, which extends laterally forward to a greater extent on one side of the light source at 17 and directs the light reflected therefrom at a lesser angle than the opposite side of the said reflecting surface at 16. Another inversely inclined surface 18 connects an outwardly inclined surface 19 to reflecting surfaces already described, the said surface 19 being likewise extended laterally forward to a greater extent at one part thereof to project the light rays in the desired directions and effect a particular form of light distribution. The reflecting surface 19 as shown by plan view, is widened out on one side of the reflector axis to effect a better distribution of the reflected light and provide a more ideal cut-off of the light for certain purposes.

Another type of reflector to which this construction is applicable is an asymmetrical reflector illustrated in Fig. 5, designed for special purposes, such as illuminating walls. This reflector may be considered as

having two axes, that which passes through the center of the neck 6 and that which forms the center of the reflecting surfaces 21, 22, 23 and 24. The neck 6 is located on one side of the center of the outwardly concave reflecting surface 20, to which an inwardly inclined surface 21 connects an outwardly inclined curved surface 22 adapted to project light rays emitted by the light source 8 out of the reflector in certain desired directions. An oppositely inclined surface 23, adapted to reflect such light rays as it may intercept to one of the said outward reflecting surfaces, connects with the surface 22 at its maximum periphery. From its minimum periphery an outwardly reflecting surface 24 extends laterally forward until the light emitted is confined to the extent desired. By carefully compounding the curvature of the surfaces 20, 22, and 24, the distribution of the reflected light, when blended with the direct rays emitted outward by the lamp, will cause a plane parallel to the axis of the lamp to be illuminated at a substantially uniform intensity, while the perimeters of the said surfaces 20, 22, and 24 may be made substantially equal, for a given size of reflector to effect such distribution of light. As it is essential that floors, walls, work benches, displays, and the like are illuminated with light of somewhat uniform intensity, reflectors must effect greater concentration of light rays at such parts of the said illuminated object as are furthest from the source of light. To realize such concentration, reflecting surfaces must be of varying curvature, that is, they must be accurately compounded or spiralled. In other words, a series of small segments of circles may be pieced together to form in a sectional view a compound curve.

In constructing a telescoped reflector as described herein, comprising a plurality of compounded reflecting surfaces, it is preferred to decrease the radii in shorter steps near the outward edge of each outwardly reflecting surface, so that inwardly inclined surfaces suspended therefrom will not obstruct reflected light. On the other hand, it is preferred to so position the inwardly inclined surfaces as to cause any light rays that may be intercepted to be reflected to an advantageous point on an outward reflecting surface.

From the foregoing description it will be seen that by constructing a succession of opposed reflecting surfaces, any degree of light distribution or concentration may be effected without substantially enlarging the maximum perimeter of the reflector, as the maximum perimeter is substantially dependent upon the size of the lamp bulb it surrounds, whereas, the maximum perimeter of reflectors heretofore constructed are dependent upon the degree of light distribu-

tion or concentration desired. Furthermore, the outwardly reflecting surfaces comprising my reflector may be made to separately form a continuation of one another, 5 as to the direction in which they reflect light, or they may be constructed independently of one another, so that part or all of each reflecting surface may reflect light outward in substantially the same direction. Their 10 individual size, contour, and relation to the light source, will, of course, vary with the distribution of light required and configuration of the light source. So that in certain cases, the reflecting surfaces may individually 15 vary in size or mean perimeter, but from the description herein given it will be readily apparent to those familiar with the art that many other forms of reflectors may be constructed according to this invention. For 20 instance, the reflector may be made elliptic or of irregular shape to effect particular forms of light distribution or to throw elliptical or somewhat rectangular beam of light. Such reflectors may either be constructed throughout of oppositely inclined 25 reflecting surfaces as described, or the opposed reflecting surfaces could be spiraled around the lamp in helical form and thus change the general direction of illumination, 30 instead of constructing reflectors as shown in Figs. 4 and 5. It will also be understood that any or all of the individual reflecting surfaces may be partially or completely corrugated or fluted to minimize striation, 35 which practice is well known. I believe that the connection of inwardly inclined surfaces to outwardly reflecting surfaces, alternately arranged and forming the walls of a light reflector, results in reflectors much 40 smaller in size than reflectors heretofore constructed for general purposes, since to effect a given light distribution, the reflecting surfaces are in closer proximity to the light source and thus the length along the 45 axis is also lessened when the light is cut off at less than ninety degrees from the lamp axis. Such reflectors are applicable to many purposes, since their relatively smaller size enables them to be enclosed within the 50 aperture of semi-opaque glass bowls, which are in common use for general lighting and where a reflector of the usual form would be too large for such purposes. Many applications and forms of the invention will thus 55 be apparent to those skilled in the art.

While I have described my improvements in detail, in connection with certain forms and improvements thereof, I do not wish to be limited to such details and forms, since 60 my invention may be made in many forms and applied to numerous uses, but what I claim as new and desire to protect by Letters Patent is:—

1. A tubular shaped light reflector, comprising a series of reflecting surfaces sur-

rounding a common longitudinal axis and each having curvature compounded individually in the axial plane, and other reflecting surfaces, said surfaces being alternately inclined outwardly and inwardly telescopically and adapted to reflect light from the same source, whereby there may be produced a desired degree of light concentration to illuminate a predetermined area with a reflector of substantially smaller maximum perimeter than a continuous reflecting surface contoured to effect a similar distribution of outwardly reflected light. 70

2. A tubular shaped light reflector, comprising a series of reflecting surfaces independently surrounding a common longitudinal axis, each of said surfaces having curvature compounded individually in the axial and transverse planes to produce a desired degree of light concentration and to illuminate a predetermined area and to prevent passage of reflected light through the source of light, said reflecting surfaces being alternately arranged telescopically with one or more inwardly inclined reflecting surfaces, whereby there results a reflector of substantially smaller maximum perimeter than a continuous reflecting surface contoured to effect a similar distribution of outwardly reflected light. 85

3. A tubular shaped light reflector, comprising a series of reflecting surfaces independently surrounding a common longitudinal axis, each of said surfaces having concave curvature compounded individually in the axial plane from various radial points so as to direct the light over a predetermined area with a desired degree of concentration and of such contour that at least a majority of the light rays reflected can not pass through the source of light, and said reflecting surfaces being connected together by one or more oppositely inclined reflecting surfaces, whereby there results a reflector of substantially smaller maximum perimeter than a continuous reflecting surface contoured to effect a similar distribution of outwardly reflected light. 100
